B. M. HAMLIN.
HATBOX FOR TRUNKS.
APPLICATION FILED JUNE 12, 1919.

1,313,223.

Patented Aug. 12, 1919.

9 11 INVENTOR.
Ben M. Hamlin,
BY Charles Shervey,
his ATTORNEY.

UNITED STATES PATENT OFFICE.

BEN M. HAMLIN, OF CHICAGO, ILLINOIS, ASSIGNOR TO J. V. MEYERING TRUNK COMPANY, OF CHICAGO, ILLINOIS, A CORPORATION OF ILLINOIS.

HATBOX FOR TRUNKS.

1,313,223.

Specification of Letters Patent.

Patented Aug. 12, 1919.

Application filed June 12, 1919. Serial No. 303,672.

To all whom it may concern:

Be it known that I, BEN M. HAMLIN, a citizen of the United States, and a resident of Chicago, Cook county, and State of Illinois, have invented certain new and useful Improvements in Hatboxes for Trunks, of which the following is declared to be a full, clear, and exact description.

This invention relates to hat boxes for wardrobe trunks and its principal object is to provide a simple, compact and practical hat box constructed and arranged to accommodate ladies' large hats and also ladies' small hats, and other articles. Another object is to provide a lady's hat box which may be converted into a plurality of trays whereby separate commodities may be packed away in each tray, one of these trays serving as a hat box for small hats. The invention 20 consists in the several novel features of construction hereinafter set forth and claimed.

The invention is clearly illustrated in the accompanying drawing, in which:

Figure 1 is a perspective view of a hat box, embodying a simple form of the present invention;

Fig. 2 is a vertical cross section thereof;

Fig. 3 is a vertical cross section, showing one of the trays adjusted to provide a double size compartment for accommodating ladies' large hats; and

Fig. 4 is a fragmental vertical, longitudinal section taken on the line 4—4 of Fig. 2.

Referring to said drawing, the reference character 5 designates a rectangular box of a height suitable to receive ladies' large hats. The width and depth of the box are made to fit the interior of one section of an ordinary wardrobe trunk, as is well understood by those skilled in the art to which this invention pertains. Said box has a front 6, back 7, ends 8, and bottom 9, secured together in any suitable manner, and a handle 10 is provided on the front by means of which the box may be withdrawn from the trunk section in which it is usually contained. On the bottom 9 of said box, a threaded stem 11 is fastened, to which is removably secured a stuffed hat ball 12, to which small hats may be pinned in the usual manner of packing them in trunks. To the inner face of the back wall 7 is secured a similar threaded stem 11^a, adapted to receive the stuffed hat ball 12, when the box is converted into a

double sized compartment for receiving ladies' large hats.

Fitting in the box 5 is a box-like tray 14 which is about one-half the depth of the main box 5, and said tray 14 is adapted to rest upon cleats 15 secured to the inner faces of the ends 8. The tray comprises a front 16, ends 17 and bottom 18, all rigidly fastened together, and a back 19 hingedly secured to the bottom 18 by hinges 20, and being capable of being swung down toward said bottom 18 when the device is converted into a double sized compartment. To the inner faces of the ends 17 of the tray are pivotally secured latches 21, which have hook-like ends 22 that are adapted to engage with keepers 23 secured to the inner face of the hinged back 19, and said latches 21, when properly engaged with the keepers 23, act to rigidly hold the hinged back in place, to form the tray 14. Buttons or latches 24 are pivotally secured to the ends 17, and are arranged to be engaged with the hinged back 19 when the latter is swung toward the bottom 18; said buttons or latches 24 act to hold said hinged back in its folded back position. Loops 25 are secured to the inner face of the ends 17 of the tray, and furnish means for facilitating the removal of the tray from the main box, and other loops 26 are secured to the outer face of the bottom 18 and facilitate the removal of the tray when it is in its inverted position; which it occupies when the device is converted into a double sized compartment.

When used as a double compartment, or double tray, the folding back 19 is held in upright position by the latches 21 and keepers 23, to form the back of the tray which rests upon the cleats 15 of the outer box. In this position each box-like member 5, 14, serves as a separate container or compartment for various things, and hats may be pinned to the stuffed hat ball 12 in the lower compartment, as is customary. To convert the hat box into a single compartment of the full depth of the outer box, the tray 14 is removed, the latches 21 disengaged from the keepers 23, the back folded down against the bottom 18, and the buttons or latches 24 swung into engagement with the folded back. The hat ball 12 is then secured on the stem 11^a, the tray 14 inverted and replaced in the box 6, with the open back of the tray

at the rear of the box. In this position the bottom 18 of the tray forms a cover for the hat box, and free space is left within the box to accommodate ladies' large hats, which 5 may be pinned to the stuffed hat ball 12.

More or less variation of the exact details of construction is possible without departing from the spirit of this invention; I desire, therefore, not to limit myself to the exact 10 form of the construction shown and described, but intend, in the following claims, to point out all of the invention disclosed herein.

I claim as new and desire to secure by Letters Patent:

1. A convertible hat box comprising an outer rectangular box having supporting ledges upon its internal wall, and an inner box of approximately one-half the depth of 20 said outer box, adapted to be removably supported by said ledges in upright position, to form, with said outer box, a double compartment, said inner box having a back hingedly secured to its bottom, and latches for 25 holding said hinged back in upright position, said inner box being arranged to be inverted, with its back folded down, and supported upon said cleats to provide a single compartment of the full depth of the 30 outer box, substantially as and for the purpose set forth.

2. A convertible hat box comprising an outer rectangular box having cleats secured upon its end walls, hat ball supports, one on

the bottom of said box, and one on the back 35 wall thereof, a hat ball adapted to be removably secured on either of said hat ball supports, and an inner box of approximately one-half the depth of the outer box arranged to rest upon said cleats in upright position 40 to form two compartments, said inner box having a back hingedly secured to its bottom, means for securing said back in upright position and means for holding said back in position folded down upon the bottom, said 45 inner box being capable of being inverted, with its back folded down upon said bottom, and supported in inverted position upon said cleats, to provide a single compartment of the full depth of the outer box. 50

3. A convertible hat box comprising an outer rectangular box having supporting cleats on its end walls, a hat ball removably secured on its back wall, and an inner box of approximately one-half the depth of the 55 outer box and arranged to rest upon said cleats in upright position to provide two compartments, said inner box having a back hingedly secured to its bottom, latches for holding the back in upright position, and 60 loops at the top and bottom of said inner box, said inner box being capable of being supported by said cleats in inverted position with its back folded against its bottom, to provide a single compartment of the full 65 depth of the outer box.

BEN M. HAMLIN.
